UNITED STATES PATENT OFFICE.

BENJAMIN GALLSWORTHY, OF PORT ARTHUR, TEXAS.

OIL-TOPPING PLANT.

Application filed July 14, 1919. Serial No. 310,533.

To all whom it may concern:

Be it known that I, BENJAMIN GALLSWORTHY, a subject of the King of Great Britain, residing at Port Arthur, in the 5 county of Jefferson and State of Texas, have invented certain new and useful Improvements in an Oil-Topping Plant, of which the following is a specification.

This invention relates to new and useful 10 improvements in an oil topping plant.

One object of the invention is to provide a device of the character described which is primarily intended for topping crude petroleum, that is, for extracting the lighter 15 elements such as gasoline and kerosene therefrom, and in the process, ridding the oil of water, leaving a residuum which is suitable for fuel oil (or which may be further treated in the process of refining the same). In 20 refining crude petroleum, particularly heavy petroleum by stills now in common use, the water contained in the oil, when heated, often causes an expansion and foaming of the oil to such a degree that the still runs 25 over, causing a waste of the oil and retarding the refining process. It is the object of this invention to provide a device of the character described whereby the water may be wholly or partially extracted from the 30 oil during a preliminary stage of refinement, and in such a manner, there will be a minimum of expansion and foaming of the oil incident to the evaporation of the water with the result that the succeeding or final 35 process will not be retarded or interfered with.

Another object of the invention is to provide a device of the character described which is simple in construction, and which 40 may be cheaply and easily erected, and which is efficient for the purpose intended.

With the above and other objects in view, the invention has particular relation to certain novel features of construction, operation 45 and arrangement of parts, an example of which is given in this specification and illustrated in the accompanying drawings, wherein:

Figure 1, is a vertical sectional view of 50 the device taken on the line 1—1 of Figure 2.

Figure 2, is a transverse sectional view taken on the line 2—2 of Figure 1, and

Figure 3, is an enlarged fragmentary end 55 view.

Referring now more particularly to the

drawings wherein like numerals of reference designate similar parts in each of the figures, the numeral 1, refers to a furnace and located adjacent thereto, there is the 60 container 2. Within this container, there are a plurality of pipes 3, arranged in vertically extending coils, one end of each pipe communicating with the furnace, and the other ends communicating with the manifold, arranged above the furnace, and leading from this manifold, there is the outlet pipe 5, connected to which is the suction fan 6, which induces a current of hot air from the furnace through the pipes 3. 65

As above stated, the pipes 3 are arranged in vertical coils, being composed of parallel sections arranged one above the other, and connected at their respective ends to form a continuous conduit. Each section of each 70 pipe is located within a hopper, said hoppers consisting of downwardly converging deflectors 7, 7, formed of metallic plates which are anchored at their respective ends to the corresponding ends of the receptacle 2, and 75 spaced a suitable distance from the respective coils of pipe. Above each coil, there is an inlet pipe 8, said pipes having their undersides perforated, and the crude oil is admitted to said pipes 8, from the manifold 9 80 into which the oil is fed through the inlet pipe 10.

When the oil strikes the heated coils, the lighter elements such as gasoline and kerosene are vaporized, and rise in the receptacle and pass into the domes 11, 11, and thence 85 out through the conduits 12, to the condenser, (not shown). The water contained in the oil is also vaporized and it is expanded incident to evaporation, causing a 90 foaming or ebullition of the oil around the coils of pipe. For this reason, the deflectors 7, 7, have been provided to confine the oil, and direct it onto the coils underneath. The oil thus gradually finds its way down 100 over the succeeding coils to the bottom of the receptacle where it is permitted to rise so as to completely submerge the lower coils. This oil is heated by said coils to the required degree to cause it to give off the 105 lighter elements, and water still retained in it, and to reduce it to the required flashing point. These submerged coils absorb the principal part of the heat from the furnace and the main refining process takes place at 110 the bottom of the receptacle where the oil rises to submerge said coils. Consequently,

the unsubmerged coils have a much lower temperature than they would otherwise have, and are not sufficiently heated to cause carbon to form on them.

- 5 As above stated, the lower turns or sections of the coils which are submerged in the oil collecting at the bottom of the receptacle, perform part of the refining process, by heating the oil collecting in said receptacle 10 to a high temperature, causing it to give off any gasoline, water or kerosene, not removed by the unsubmerged coils, necessary to bring the residual oil to test, and the heat of the unsubmerged coils, which would 15 otherwise be wasted is utilized as described, in a preliminary step of the process to free the oil of a portion of its water and its lighter elements.

If the receptacle is not insulated, there 20 will be a certain amount of condensation on the inner walls of the receptacle 2, and this will trickle down into the trough at 3, carried by the inner wall of the receptacle near the bottom thereof, and may be led off out 25 through the outlet conduits 14, 14. A gauge 15 is provided at one end of the receptacle to indicate the amount of oil therein and leading from the bottom of the receptacle, there is a drain pipe 16, from which the

heavier residuum collected in the receptacle 30 may be drawn off to be used as fuel or for further refining as desired.

What I claim is:

A device of the character described, including a receptacle, a furnace arranged adjacent thereto, an outlet manifold, flue pipes connected at one end directly into said furnace and arranged in vertical coils, in said receptacle and their other ends terminating in said manifold, oil inlet pipes arranged above the respective coils and whose undersides are provided with perforations through which crude oil may be discharged onto the respective coils, downwardly converging baffles arranged on opposite sides of each 45 of the respective turns of the coils and having their lower edges spaced apart throughout their length, and provided to direct the oil passing over each turn down onto the turn underneath, and an outlet leading from 50 the receptacle above the lower coils.

In testimony whereof I have signed my name to this specification in the presence of two subscribing witnesses.

BENJAMIN GALLSWORTHY.
